UNITED STATES PATENT OFFICE.

MORITZ FORST, OF NEW YORK, N. Y., ASSIGNOR OF ONE-THIRD TO MOSES BEILECH
AND ONE-THIRD TO MINNIE BERN, BOTH OF NEW YORK, N. Y.

COMBINED FAN AND WHIP.

951,271.

Specification of Letters Patent. Patented Mar. 8, 1910.

Application filed September 23, 1909. Serial No. 519,241.

To all whom it may concern:

Be it known that I, MORITZ FORST, a citizen of Austria, residing at New York city, Manhattan, county and State of New York, have invented new and useful Improvements 5 in Combined Fans and Whips, of which the following is a specification.

This invention relates to a combined fan and whip provided with a common slidable 10 handle which serves to open or close the fan and is held against movement when the device is used as a whip.

In the accompanying drawing: Figure 1 is a front view of my combined fan and 15 whip, showing the fan open; Fig. 2 is an enlarged top view thereof, showing the fan closed; Fig. 3 a longitudinal section on line 3—3, Fig. 2; Fig. 4 a similar section on line 4—4, Fig. 2, with the covering 20 omitted, and Fig. 5 a cross section on line 5—5, Fig. 3.

The flexible web 10 of the fan is fluted 25 radially so that when opened it will assume a circular shape. To its center or inner end there are secured to web 10 a pair of oppositely placed first tapes 11 and a pair of similarly placed second tapes 12, the latter extending at right angles to the former. Web 10, when folded, is adapted to be received 30 within a tubular casing 13, to the lower end of which is secured a stick or whip-rod 14. The connection between the latter and casing 13 is shown to be effected by means of a bent strap 15 fitted on the 35 upper tapering end of rod 14 and engaged by a pin 16 extending diametrically across the open lower end of casing 13. This casing is telescoped by a tubular handle 17 provided at its lower end with a conical tip 18 40 which encircles rod 14 upon which it is guided.

Tapes 11 pass upward within casing 13, then over the upper edge thereof and then downward between said casing and handle 45 17. The ends of the tapes extend outwardly through a pair of diametrically arranged slots 19 formed near the top of handle 17, to the outer side of which they are pasted. Tapes 12 pass downward within casing 13,

then around the lower edge thereof, and 50 then upward between the casing and handle 17. Their ends extend outward through slots 20 at the top of handle 17 to which they are pasted. A third pair of tapes 21 are connected at one end to the flanking 55 folds of web 10 near the circumference of the latter and pass with their other end through slots 22 formed in handle 17 directly above slots 19. These tapes 21 are also pasted to the outer side of handle 17 60 which is provided with a covering 23. In order to guide casing 13 in an axial direction, the ends of pin 16 are extended outwardly to engage a pair of longitudinal 65 grooves 24 formed in handle 17.

If the fan is folded it is entirely inclosed 70 within casing 13 which is, in turn, concealed within handle 17. By pushing the latter down along rod 14, a pull will be exerted on tapes 11 which will thus raise web 10 out of casing 13 and simultaneously unfold the 75 same owing to the action of tapes 21. If the handle is pushed up the web will be folded and drawn into casing 10 by tapes 12. It will be seen that by sliding the handle up 80 or down, the fan may be readily closed or opened. At the same time the connection between the handle and web prevents the former from slipping when the device is used as a whip.

I claim:

1. A device of the character described, comprising a tubular casing, a rod connected thereto, a tubular handle slidable on the casing and rod, a foldable fan adapted to be 85 inclosed within the casing, and tapes that operably connect the handle to the fan.

2. A device of the character described, comprising a tubular casing, a rod connected thereto, a tubular handle slidable on the 90 casing and rod, a foldable fan adapted to be inclosed within the casing, a first pair of tapes extending from the fan to the handle around the top of the casing, and a second pair of tapes extending from the fan to the 95 handle around the bottom of the casing.

3. A device of the character described, comprising a tubular casing, a rod connect-

ed thereto, a tubular handle telescoping the casing, means for axially guiding the handle upon the casing, a coniform tip on the handle engaging the rod, a foldable fan adapted to be inclosed within the casing, and tapes that operably connect the handle to the fan.

Signed by me at New York city, (Manhattan,) N. Y., this 22d day of September, 1909.

MORITZ FORST
